COOLING BED STOP

Myles Morgan and Ernest R. Comtois, Worcester, Mass., assignors to Morgan Construction Company, Worcester, Mass., a corporation of Massachusetts

Application December 19, 1955, Serial No. 554,078

1 Claim. (Cl. 80—42)

This invention relates to a cooling bed and more particularly to apparatus arranged to handle the product of a rolling mill.

It is common practice in steel mills to introduce the product of a rolling mill to a cooling bed after rolling. The cooling bed serves several purposes among which is the principal purpose of permitting the rolled material to cool to the point where it may be handled without fear of deformation. In addition, the cooling bed provides a storage facility and at the same time provides for the lateral movement of the product to bring it into alignment with machinery which may not be on the center line of the rolling mill. A product of the rolling mill, which may be rod, bar or the like is transferred to the cooling bed in very long lengths. It is necessary, then, that the product be cut into shorter lengths, for storage and sale. A popular length into which the bar may be cut is that length which will permit it to be inserted in a railway gondola car. Because of the speed at which lengths of bar are being presented to the cooling bed and the time required to cut the bar into the short lengths, it is usual practice to present the bar to the shear in groups of a dozen or more and, for this purpose, it is necessary that all the bar lengths be coextensive with one another. In the past, it has been the practice to place a large number of bars on the approach table which precedes the shear, and, because the bar has been placed on the cooling bed in a more or less hit or miss fashion, the lengths of bar will not be coextensive with one another. In the past it has been the practice to place a stop between the ends of the bar and the shear and to drive the shear approach table until all the forward ends of the bar strike the stop. Not only is this time consuming, but it is necessary for the driven rolls which make up the working elements of the approach table to slip under the bar which reaches the stop first. This, of course, results in scoring of the rolls, so that they have to be replaced in a very short length of time. These and other deficiencies of the prior art apparatus have been obviated by the present invention in a novel manner.

It is, therefore, an outstanding object of the present invention to provide a cooling bed wherein the lengths of rolled products are aligned and made coextensive during their passage therover.

Another object of the present invention is the provision of means for rendering long lengths of material coextensive.

It is a still further object of this invention to provide cooling bed apparatus in which rolled products passing thereover may be adjusted lengthwise by a desired amount.

Another object of the invention is to provide cooling bed apparatus for the lengthwise adjustment of rolled product which apparatus is rugged and dependable and which requires a minimum of maintenance.

With these and other objects in view as will be apparent to those skilled in the art, the invention resides in the

2

combination of parts set forth in this specification and covered by the claim appended hereto.

The character of the invention, however, may be best understood by reference to certain of its structural forms 5 as illustrated by the accompanying drawings in which:

Figure 1 is a sectional view of apparatus embodying the principles of the present invention taken transversally of the center line of the rolling mill.

Figure 2 is a plan view, somewhat enlarged, of a portion 10 of the apparatus shown in Figure 1.

Figure 3 is a plan view somewhat enlarged of another portion of the apparatus shown in Figure 1, and

Figure 4 is a transverse elevational view of the apparatus shown in Figure 3.

Referring first to Figure 1, wherein is best shown the general features of the invention, a cooling bed, indicated generally by the reference numeral 10, is shown in use in conjunction with a rolling mill runon table 11, and a cold runoff table 12. The rolling mill runon table 11 consists of driven rollers 13, which are aligned with the center line of the rolling mill and are driven by motors 14. A rotary kickoff mechanism 15 is mounted above the rollers 13, and provides for moving the rolled products laterally from the rollers 13. The rolling mill runon table 11 is suitably mounted on supports 16 which are fastened to a suitable foundation 17. The cold runoff table consists of a series of driven rollers 18 and flat plates 19, extending between the rollers, the rollers having their uppermost surfaces extending slightly above the plates 19. The rollers are driven through gearing 20, lying within a housing 31 which forms part of the runoff table. The runoff table is also mounted on the foundation 17 of the mill. Extending laterally from the runon table 11 are a series of stationary racks 21. Interspersed 25 among the stationary racks are a number of carryover racks 22. These sets of racks are provided with notched upper edges in the usual manner. Each of the carryover racks is mounted on vertical connecting rods 23 and 24 which are mounted for eccentric movement on crankshafts 25 and 26. These shafts are driven by a main drive 27 through gearing, not shown, lying within a gear box 28. A turnbuckle connecting means 29 provides for structural rigidity between the two connecting rods. At the end which lies away from the runon table 11, each 30 of the stationary racks 21 is provided with an aligning roller 30 which will be described more clearly hereinafter. Extending between the racks 21 and 22 and the cold runoff table 12 are a series of shuffle bars 32, some of which are fixed and others of which are movable. 35 Adjacent to the end which is away from the runoff table 12 each of the movable shuffle bars 32 is connected by a connecting rod 33 to an eccentric 34. The shuffle bars 32 extend into the runoff table and portions of the plates 19 are cut away to permit vertical movement of these bars. At the end which underlies the runoff table, the movable shuffle bars are contacted by a crank arm 35, which is keyed to a rotatable drive shaft 36. The other 40 end of the crank arm is provided with a roller 37 which contacts the under side of the shuffle bar on occasion.

Referring now to Figure 2, wherein is best shown the details of the aligning roll 30, the roll is shown as having conical surfaces, such that a section through the roll gives a notched configuration which would be a continuation of the notched upper surface of the stationary rack 21. The aligning roll is provided at the end which faces the runon table 11 with a shaft 40 mounted in a bearing 41. At the other end, a shaft 42, extends through a bearing 43 and is provided at its outer end with a pulley 44. The pulley 44 is connected by belts 45 and an output pulley 46 to a reduction unit 47 driven by a motor 48. Generally speaking, each of the stationary racks 21 which contains an

aligning roll 30, is provided with two vertical notched walls 50 and 51 which are joined by a horizontal web 52 in the area which contains the aligning roll 30. The stationary rack 21 is provided with a yoke configuration 53 which is best shown in Figure 1.

As is evident in Figures 3 and 4, certain of the stationary racks are formed somewhat differently from those described heretofore. A number of the stationary racks, indicated by the reference numeral 21a, are not provided with an aligning roller 30. But the general arrangement of double vertical walls joined by a horizontal web is maintained. In addition, the vertical walls are joined by a wall extending between them at the ends adjacent the cold runoff table 12. On this type of stationary rack may be mounted a stop member 55 which comprises a main body portion 56 adapted to be arranged transversely of the roll mill pass so that it lies between the two vertical walls of the stationary rack 21a. At one end, the main wall 56 is formed with a downwardly depending leg 57, adapted to rest on a horizontal web of the stationary rack. At the same end and extending sideways therefrom are abutment plates, 58 and 59, which extend between the vertical transverse walls of the shuffle bar and prevent sidewise movement of the stop member 55. At the other end of the main plate, 56, is a welded plate 60, which extends sidewise therefrom and which has welded thereto a downwardly depending finger element 61. The finger element 61, is adapted to hook over a longitudinal vertical web, which extends between the transverse vertical webs of the stationary rack. A handle 62 extends upwardly of the stop member centrally thereof.

The operation of the invention will now be clearly understood in view of the above description. Lengths of bar emanating from the rolling mill arrive on the runoff table 11 on the upper surface of the rollers 13 which are rotated at a high rate of speed by the motors 14. Presumably, a flying shear will be located between the rolling mill and the runoff table 11 to sever the bars into convenient long lengths. As each length arrives beside the cooling bed, the rotary kickoff mechanism 15 rotates causing the length of bar to be projected laterally into first notch of the stationary racks. Eventually, the carryover racks 22 under the control of the drive shaft 27 and the crankshafts 25 and 26 move upwardly in a circular path, engage the bar in the first notch and carry it over to the second notch of the stationary rack. In this way, each bar is moved from one notch to another across the cooling bed. Eventually, it is deposited in the first notch of the aligning roll 30. These rolls are driven by the motor 48 through the gear reduction unit 47, the belt 45, the pulley 44, and the shaft 42. A rotation of the aligning roll causes the bar to be projected lengthwise of the cooling bed, i.e., parallel to the center line of the rolling mill. Eventually, the rod strikes the stop member 55, which has been placed on a suitable fixed shuffle bar 21a. After striking the stop member 55, the bar can now go no further and remains in the first notch of the aligning roll 30 until it is lifted by the movable shuffle bars 22 into the next notch of the aligning roll 30. From there, the carryover racks 22 carry the bar onto the secondary shuffle bars 32. Since these

shuffle bars have no notches and the throw of the eccentric 34 is selected to be very small, the bars proceed very slowly across the shuffle bars 32. In this way they accumulate in a side-by-side relationship. During this period the crank arm 35 is in a lower position so that the shuffle bars lie below the surface of the runoff table rolls 18. Since the shuffle bars are below the level of the rollers 18, and the plates 19, even in the uppermost position of throw of the eccentric 34, none of the bars are transferred over to the roll 18, and the bars accumulate adjacent thereto. Eventually, the shaft 36 is rotated so that the crank arm 35 moves into a vertical position and the roller 32 pressing against the shuffle bars lifts them into an uppermost position where their upper edge is higher than that of the rolls 18. In this condition, the shuffling of the bars causes the bars to proceed to positions overlying the rolls 18 of the approach table 12. When a sufficient number of bars have been moved to this position over the rolls 18, the shaft 36 is actuated to cause the arm 35 to retract to a lower position and the bars are dropped onto the upper portions of the rolls 18. In this way, a considerable number of bars will be lowered onto the rolls at the same time. Naturally, these bars have been aligned by the aligning roll 30 and lie in coextensive relationship. Then the rolls 18 are rotated by the gear mechanism 20 in the housing 21 of the runoff table and the bars proceed in a body to the shear. At the shear all the front ends will be cropped at the same time and the bars will be cut as a unit to the desired lengths.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described what is claimed as new and desired to secure by Letters Patent is:

A stop member for use on a bar cooling bed having movable and stationary racks and having driven aligning rolls associated with the stationary racks at the discharge side of the bed, comprising a main body portion adapted to extend in a vertical plane in line with the rollers to determine the positions of the ends of the bars, abutment plates extending from one end of the main body portion adapted to prevent sideways movement of the stop member, a leg extending downwardly from one end of the main body portion adapted to rest on the stationary rack, and a finger element extending downwardly from the other end adapted to prevent movement of the stop member in a direction parallel to the rack.
